UNITED STATES PATENT OFFICE.

BARCLAY MILTON ARMITAGE, OF MINNEDOSA, MANITOBA, CANADA.

MEANS FOR UTILIZING WATER-POWER.

SPECIFICATION forming part of Letters Patent No. 337,727, dated March 9, 1886.

Application filed July 20, 1885. Serial No. 172,151. (No model.)

To all whom it may concern:

Be it known that I, BARCLAY MILTON ARMITAGE, a subject of the Queen of Great Britain, residing at Minnedosa, in the Province of Manitoba, Canada, have invented certain new and useful Improvements in Means for Utilizing Water-Power, of which the following is a full, clear, and exact description.

The object of my invention is to so construct and arrange the operating parts of a mill in connection with the dam or reservoir that the operating stream or head of water is conducted and discharged at such a distance from the surface as to insure its freedom from the effects of ice and frost, and to utilize the greatest amount of head.

In the accompanying drawings, illustrating my invention, in the different figures of which corresponding parts are designated by similar letters of reference, Figure 1 is a plan view, and Fig. 2 is a vertical section.

a designates the dam or reservoir, which may be of any ordinary construction. A feed-pipe, b, is connected with the reservoir or dam as near to its bottom as practicable, and in such a manner that it will be water-tight at the joint. This pipe may be laid horizontally or at an incline, to suit the nature of the ground or the fall in the stream, and in such manner as to allow the water, after passing through the wheel, to flow through the discharge-pipe f without the interference of backwater. This feed-pipe b connects with the flume or penstock c, which is provided near its bottom with a floor or bottom, d'. One or more openings are made in the bottom d', in which are located the water-wheels d. A discharge-pipe, f, leads from the chamber c' at the lower end of the flume or penstock, and preferably empties into the river or stream near its bottom, and at such a depth that the water will not freeze around the opening thereof. A filling, e, of earth or other material covers and surrounds the pipe b, flume or penstock c, and discharge-pipe f, which will effectually prevent the freezing of water in those parts.

If the water-wheels d be of the construction ordinarily seen in turbines, they will be provided with vertical shafts l, having suitable

gear or belt wheels for transmitting the power, 50 as desired.

The feed-pipe b may be provided with a grating, k, placed at an angle or incline thereto. This grating will prevent the entrance of such foreign matter as would interfere with the flow of water or the proper operation of the wheels. Being placed at an incline, the tendency of the flowing water will be to force any accumulation therefrom.

By locating the pipe b at the bottom of the dam or reservoir it will be seen that the flow of water is never impeded or prevented by the freezing of water. The same result is effected by locating the opening of the discharge-pipe f at the bottom of the river or stream. The 65 mill can thus be kept in constant operation through the entire winter. By locating the opening of the pipe d at the bottom of the reservoir, I am also enabled to utilize the greatest possible head of water.

A suitable wasteway, h, is provided at the top of the dam or reservoir.

What I claim as my invention, and desire to secure by Letters Patent, is—

1. The combination, with a reservoir or 75 dam, of a pipe connected therewith near its bottom and provided with a grating set at an incline with the opening in said pipe, said pipe leading to a flume or penstock containing water-wheels and a discharge-pipe connected with the bottom of another body of 80 water at a lower level than the level of the reservoir or dam, substantially as and for the purpose set forth.

2. The combination, with the dam and the 85 penstock c, of the pipe connecting the penstock and dam, said pipe being provided with a grating set at an incline with the opening in the pipe, the water-wheel located in the opening of the penstock, the chamber below the 90 water-wheel, and the discharge-pipe, substantially as set forth.

In testimony whereof I affix my signature in presence of two witnesses.

BARCLAY MILTON ARMITAGE.

Witnesses:

GEO. A. MORPHY,
JAMES A. GRIFFITH.
